[57] CLAIM

The ornamental design for a mulch spreading apparatus, as shown and described.

DESCRIPTION

FIG. 1 is a front elevational view of the mulch spreading apparatus showing my new design, the hitch member being positioned to correspond generally to the orientation thereof when attached to a small tractor;

FIG. 2 is a rear elevational view thereof;

FIG. 3 is a left side elevational view thereof;

FIG. 4 is a right side elevational view showing the discharge area of the mulch spreading apparatus shown in FIGS. 1-3;

FIG. 5 is an upper left side perspective view showing the top thereof and internally of the hopper looking at the discharge mechanism adjacent the right side thereof; and,

FIG. 6 is a top plan view thereof.
